UNITED STATES PATENT OFFICE

JAMES DOUGLAS VOSS, OF OAKLEIGH, NEAR MELBOURNE, VICTORIA, AUSTRALIA

BREATHING APPARATUS

Application filed May 19, 1927. Serial No. 192,760.

This invention refers to apparatus for delivering oxygen and the like in cases of asphyxia and means combined with such apparatus for neutralizing poisonous gases, and has been devised with the object of providing simple and efficient means whereby workers in areas where poisonous gases are prevalent may perform their duties without fear of inhaling the fumes surrounding them. 10 Furthermore, the apparatus embodies means whereby poisonous gases are neutralized before reaching the nostrils or mouth of the worker.

Apparatus for the purpose above mentioned has been described in prior Commonwealth Patent No. 24591/25 and the present invention embodies additional features and a considerably simplified construction of apparatus.

20 The basic principle underlying the present invention consists in the use of a cylinder housing a gas regulating means operable by means of the incoming supply of such gas, means for supplying the gas to a mask, and means for neutralizing poisonous gases encountered by the wearer.

One of the essential features of the invention consists in the use of a sleeve valve for supplying oxygen to those requiring it, such 30 valve being formed by mounting a toothed wheel on a hollow spindle provided with a gas inlet, the spindle supporting means being hollow so that a passage is opened from the cylinder, in which the sleeve valve and adjacent parts are housed, to the mask upon each revolution of the toothed wheel.

The toothed wheel meshes with a worm formed on or integral with a rotor provided with vanes or pockets on its periphery, the 40 oxygen inlet being disposed to direct a stream of oxygen upon said vanes or pockets so causing the rotor to spin.

By so doing, the toothed wheel is caused to revolve and as the oxygen is under pressure in the cylinder, small quantities are permitted to flow into the sleeve valve, thence to the mask, on each revolution, the number of revolutions governing the amount of oxygen permitted to flow to the mask, as it is evident that the sleeve valve will open more frequently, at a high rate of speed than at a slow rate.

In order to more readily understand the invention, reference will now be made to the accompanying drawings in which:—

55 Figure 1 is a view showing main portions of the invention before assembly.

Figure 2 is a detail view showing gas inlet and regulating means.

Figure 3 is a vertical central section showing gas neutralizing chamber.

Figure 4 is a view showing the gas mask and,

Figure 5 is a detail view showing sleeve valve arrangement.

According to this invention a cylinder 5 is provided having pivotally mounted arms 6 adapted to hold the cap 7 supporting the gas neutralizing chamber 8, the cap 9 carrying the gas regulating means being received on 70 the end of the cylinder to which it is shown adjacent in Figure 1.

The gas regulating means comprises a rotor 10 which is under the cap 9, said rotor 10 being mounted on the spindle 11 formed in 75 the manner of a worm as at 12.

The rotor 10 is provided on its periphery with a series of pockets or vanes 10' such pockets or vanes being adapted to receive a charge of oxygen or the like against them in 80 similar manner that a turbine receives steam, thus, when the incoming pressure of oxygen from a suitable oxygen cylinder (not shown) impinges against the pockets, or vanes, on the rotor 10, said rotor is caused 85 to spin.

The spinning of the rotor 10 causes the worm 12 to rotate and in so doing, the toothed wheel 13 moves also, said toothed wheel having a boss 14 with an orifice 15 therein which is adapted to register with an orifice 16 in the spindle support 17, the said support 17 being hollow by providing a passage way 18 therein which communicates with the tube 19 communicating with the gas mask 20.

90 The oxygen after rotating the rotor 10 enters the compartment 21 of the cylinder 5 where it is obvious a certain pressure sets up and as the rotor 10 continues to spin, the orifice 15 in the boss 14 of the toothed wheel 100

13, registers with the orifice 16 in the hollow support 17, thus permitting a quantity of oxygen to flow to the pipe line 19 which engages with the pipe line 19^a which passes into a short pipe member 22 on the cap 7.

5 It will be obvious that according to the pressure of the incoming charge of oxygen, so the rotor will spin fast or slow and consequently the worm 12 causes the toothed wheel 13 to correspondingly rotate, thus causing the orifice 15 to register with the orifice 14 more or less frequently.

Upon the side of the cylinder and below the partition 23 which forms the bottom of the 15 chamber 21 of the cylinder 5, is an inlet cap 24 provided with a plurality of openings 25 through which poisonous gases are adapted to pass and before such gases can reach the short pipe 22, they pass through a neutralizing chamber 8 shown more particularly in 20 Figure 3. This chamber is adapted to be fitted to the cap 7 by forming a screwed extension 7^a on the end of the chamber 8 which is adapted to engage with a correspondingly 25 screwed portion 7^b formed in the short pipe 22.

Within the chamber 8 are a series of partitions 8^a which are spaced apart as shown and these partitions are formed of perforated 30 material preferably of the nature of wire gauze.

The gases, on entering the cap 24, pass upwardly through the inlet 26 where, on passing through the lower gauze partition 8^b, percolates through cotton wool or like material 8^c, thence through the gauze partition 8^a where they meet a layer 27 of 150 cubic centimetres of activated charcoal, they then percolate through a further layer of wire gauze 8^b, 40 cotton wool 8^c, and gauze 8^a to meet a layer 28 of 200 cubic centimetres of fused caustic on pumice, then through gauze 8^b, cotton wool 8^c and gauze 8^a to pass through a layer 29 of 250 cubic centimetres of calcium chloride. 45 They then pass through a further gauze 8^b, cotton wool 8^c, and gauze partition 8^a to meet a layer 30 containing 400 cubic centimetres of hopcalite, thence upwardly through a gauze partition 8^b, cotton wool 8^c, and gauze 8^a, 50 where they pass through a composition in the space 31 comprising 450 cubic centimetres of silica gel, and upon passing through this latter component the gases are then neutralized and prior to passing through the outlet 7^a, 55 they pass through a further wire gauze 8^a and cotton wool 8^b, and finally a gauge 8^c.

The gases thus neutralized pass through the short pipe 22 thence upwardly to connect the mask 20 via the pipe 32.

60 I do not make any claim for the particular construction of mask with the exception that a flexible pipe 33 is vulcanized or otherwise affixed between the eye pieces 34, this pipe being the oxygen supply means and is adapted to engage with the pipe 19^a where it pro-

jects beyond the edge of the short pipe 22.

The pipe 33 not only supplies the oxygen to the wearer but also keeps the eye pieces 34 clear for vision as it will be obvious that with the wearer breathing into such a small space as a gas mask, although most of the exhaled air passes outwardly through the valves 35, that within the gas mask certain condensation occurs which fogs the eye pieces 34 and by providing an orifice 36 on the pipe line 33, the oxygen is caused to be directed on to the eyepieces, thus preventing condensation and thereby maintaining the eye pieces 34 perfectly clear under all conditions and permitting the user to work without being hampered by dulled glasses.

70 The oxygen supply cylinder (not shown) is connected to the apparatus described by means of a flexible or other pipe line which engages with the screw boss 9^a formed on the cap 9, a small orifice 9^b permitting the said oxygen to impinge against the rotor 10.

The oxygen supply to the wearer of the mask 20, may be regulated by means of the pin valve 37 which functions in the well known manner, that is, to close or open, or partly so, the passage to the pipe 19 from the chamber 21.

75 I do not wish to limit myself to the use of oxygen as it will be apparent from the foregoing description that an anaesthetic may be administered by the apparatus described, or, in the case of pulmonary complaints, intermittent doses of glycerine and oxygen may be administered as previously described in prior Commonwealth Patent referred to.

80 The salient features of the present invention and those for which I desire to secure protection are the particular means for supplying intermittent doses of a gaseous element to a patient or to the wearer of a mask in dangerous areas and to the combination therewith of gas neutralizing means as herein described, the apparatus as described is compact, small and of no great weight, permitting it to be carried, together with the mask and necessary oxygen supply cylinder, 100 without effort.

85 What I claim as my invention and desire to secure by Letters Patent is:—

1. Apparatus for the purpose described comprising a casing having means separating it into an oxygen-receiving chamber and a chamber for receiving a purifying canister, 110 closures for said casing, an oxygen regulating device being carried in toto by one closure, a purifying canister carried by the other closure, the latter closure being provided with a discharge nipple for said canister adapted to be connected to a mask, means connecting the discharge of said oxygen regulating device with said nipple, and an inlet intermediate the ends of said casing for admitting poison gases to said canister.

115 2. Apparatus as claimed in claim 1, the 120

oxygen regulating device including a connection adapted to be put in communication with a supply of oxygen under pressure, a rotor, actuated by the velocity of the oxygen from said supply, and a periodically opening valve actuated by said rotor.

3. Apparatus as claimed in claim 1, the oxygen regulating device including a connection adapted to be placed in communication with a supply of oxygen under pressure, a rotor actuated by the velocity of the oxygen from said supply, and a periodically opening valve actuated by said rotor, said valve including a sleeve, and a hollow boss acting as a support for said sleeve, the passage within said boss being in communication with the outlet of said regulating device, said sleeve being formed with an aperture registering with the passage in said boss at each revolution of said sleeve, and gearing carried by said sleeve operatively connected to said rotor.

Signed at Melbourne, Victoria, Australia,
this 8th day of April, 1927.
